L. STEINBERGER

TELEPHONE OR OTHER SOUND RECEIVER

Filed Jan. 21, 1921

Fig. 1.

Patented May 22, 1923.

1,455,817

UNITED STATES PATENT OFFICE.

LOUIS STEINBERGER, OF BROOKLYN, NEW YORK.

TELEPHONE OR OTHER SOUND RECEIVER.

Application filed January 21, 1921. Serial No. 438,851.

To all whom it may concern:

Be it known that I, LOUIS STEINBERGER, a citizen of the United States, and a resident of the borough of Brooklyn, city and State of New York, have invented certain new and useful Improvements in Telephone or Other Sound Receivers, of which the following is a specification.

My invention relates to sound receivers particularly adapted for use in telephone systems or in talking machines whereby the equalization of air pressure may be effected on both sides of the diaphragm.

One of the objects of the invention is to provide a sound receiver so constructed that the diaphragm is held in place by clamping means effective throughout its periphery and means being also provided for permitting free passage of air from the upper to the lower side of the diaphragm around the edge thereof, thereby equalizing the air pressure thereon and permitting more effective operation of the diaphragm.

Other objects will appear from the subjoined specification and claims.

In the drawings:

Fig. 1 is a view partly in section and partly in elevation of a telephone sound receiver embodying my invention.

Fig. 2 is a horizontal section of the lower portion of the sound receiver on line 2—2 of Fig. 1.

Fig. 3 is a view similar to Fig. 1 of a modified structure embodying my invention.

In the drawings, 5 designates the exterior casing of a telephone receiver, the same being made either of electrose or hard rubber or of a suitable non-metallic insulating material having an open end across which the vibratory diaphragm 6 extends and upon which it is supported. The diaphragm is held in place by a cap 7 made of material similar to that of which the casing is made and having threaded connection therewith at 8 apart from the diaphragm whereby a chamber 9 is provided between the cap and the diaphragm leading to the atmosphere through an opening 9, and a chamber 10 is also provided on the underside of the diaphragm, as clearly shown in the drawing. The cap is so formed that there are two flanges projecting downwardly from the underside thereof, namely the flange 11 and the flange 12. Each of these flanges are situated apart from each other so as to form when the cap is in place a chamber 20 which, when the cap is mount-

ed upon and secured to the lower portion of the sound receiver, extends from a point above the diaphragm to a point below the same and surrounds the edge thereof. The lower portion of the flange 12 is screw-threaded on the inner side so as to engage with screwthreads on the outer surface of the casing of the receiver at 8 to effect an engagement therewith to hold the cap and diaphragm in place.

The lower portion of the receiver casing 5 has projecting upwardly therefrom a flange 13 upon which the diaphragm 6 rests and against which the diaphragm is clamped by the under side of the flange 11 of the cap when the cap is screwed into place. It will thus be seen that the diaphragm is rigidly and permanently held in place around its periphery by being clamped by the flanges 11 of the cap and 13 of the lower portion of the receiver so there may be no danger of the diaphragm buckling in any way.

Air and sound communication between the chamber 9 and the chamber 20 is effected by means of a plurality of conduits 30 extending through the flange 11, and likewise communication between the chamber 10 and the chamber 20 is effected by a plurality of conduits 40 extending through the flange 13. This arrangement of air conduits is effective to provide air communication from the chamber 9 through the chamber 20 to the chamber 10, and consequently provides for an equality of air pressure on both sides of the diaphragm.

The structure illustrated in Fig. 3 is fundamentally the same as the structure shown in Fig. 1, but in the structure of Fig. 3 I have provided another specific form of cap with an independent coupling to secure the cap in place to the lower portion 5 of the sound receiver and thus secure the diaphragm between the flange 11 of the cap and the flange 13 of the sound receiver. The lower portion of the sound receiver shown in Fig. 3 is exactly the same shape and formation as the lower portion of the sound receiver of Fig. 1, the cap however, differs in that the downwardly projecting flange 12 of Fig. 1 is omitted and in lieu thereof there is provided a horizontally projecting flange 12' extending outwardly from the cap. A coupling member 50 which may be either made of metal or insulating material is cylindrical in shape and has a horizontally dis-

posed flange 51 projecting inwardly at one end to engage the upper surface of the flange 12' and is screwthreaded at 52 at the lower end to engage the screwthreads 8' which are 5 formed on the outer upper portion of the telephone receiver 5, and thus hold the cap and diaphragm in place on the lower portion of the receiver structure.

After the diaphragm 6 is placed in position 10 on the top of the flange 13 of the receiver 5 and the cap is placed in position so the flange 11 rests upon the upper surface of the diaphragm adjacent its outer edge, then the coupling member 50 is screwed 15 down into place so that the flange 51 bears against the flange 12' of the cap 7 and holds the cap firmly down upon the diaphragm, thus clamping the diaphragm in place, as clearly shown. The cap 7, diaphragm 6, 20 lower member 5 being assembled and clamped in place by the coupling 50, it will be noted that the shape of the elements are such that a chamber 20' will be formed by the flanges 11 and 13 and the coupling member 50, which chamber extends around the edge of the diaphragm and communicates with the chamber 9 by means of a plurality of conduits 30 extending through the flange 11 and with the chamber 10 underneath the 25 diaphragm by means of a plurality of conduits 40 which extend through the flange 13.

The magnet elements, in the interest of clearness, are not shown, and it is deemed sufficient only to say that they may be of any 35 suitable form as my invention is in no way concerned with the details of the magnet whereby the diaphragm is caused to vibrate.

The construction above described is simple 40 and effective for providing a uniform clamping means for the diaphragm and for also providing equal air pressure on both sides of the diaphragm and thereby causing the diaphragm to be more sensible to the sound vibrations and to permit more effective operation thereof.

As changes of construction could be made within the scope of my invention, it is in-

tended that all matter contained in the above description or shown in the accompanying drawings shall be interpreted as illustrative 50 and not in a limiting sense.

Having thus described my invention what I claim as new and desire to secure by Letters Patent is:

1. A telephone receiver comprising a casing 55 with a longitudinally extending perforated annular flange formed at one end thereof, a diaphragm seated on said flange, and a cap secured to said casing having a perforated annular flange engaging the opposite 60 side of said diaphragm and adapted to exert an even pressure on the outer peripheral margin of the diaphragm, the said perforations leading into an annular chamber 65 formed between the casing and cap.

2. A telephone receiver comprising a casing 70 having an inner annular flange projecting longitudinally and an outer screw threaded portion, a cap having an outer flange, means for engaging said cap with 75 said outer screw threaded portion and an inner flange spaced away from said outer flange to form an annular chamber between the cap, casing and engaging means and a diaphragm whose peripheral margin is held between said inner flanges each of said inner flanges being perforated.

3. A telephone receiver comprising a casing 80 having an inner annular flange projecting longitudinally and an outer screw threaded portion, a cap having an outer flange engaging with said screwthreads and an inner flange spaced away from said outer flange to form an annular chamber and a 85 diaphragm whose peripheral margin is held between said inner flanges, each of the said inner flanges having openings therethrough communicating with said annular chamber.

In witness whereof, I have hereunto set my hand at the borough of Manhattan, city 90 and State of New York, this 14 day of January, 1921.

LOUIS STEINBERGER.
